UNITED STATES PATENT OFFICE

171,566

ASPHALT PATCHING MACHINE

William H. Wylie, Oklahoma City, Okla.

Application May 13, 1953, Serial No. 24,987

Term of patent 14 years

(Cl. D14—3)

To all whom it may concern:

Be it known that I, William H. Wylie, a citizen of the United States, residing at Oklahoma City, State of Oklahoma, have invented a new, original, and ornamental Design for an Asphalt Patching Machine, of which the following is a specification, reference being had to the accompanying drawings, forming a part hereof.

Figure 1 is a perspective view looking at the front end and right side of an asphalt patching machine made in accordance with my new design;

Figure 2 is a similar view looking at the rear end and left side of the machine;

Figure 3 is an elevational view looking at the right side of the machine;

Figure 4 is a similar view looking at the left side of the machine; and,

Figure 5 is a top view of the machine.

I claim:

The ornamental design for an asphalt patching machine, as shown.

WILLIAM H. WYLIE.
